UNITED STATES PATENT OFFICE.

PAUL MEDIATE, OF CLEVELAND, OHIO.

BOAT-PROPELLED MECHANISM.

Application filed January 16, 1926. Serial No. 81,844.

To all whom it may concern:

Be it known that I, PAUL MEDIATE, a citizen of the United States, residing at Cleveland, in the county of Cuyahoga and State of Ohio, have invented new and useful Improvements in Boat-Propelling Mechanism, of which the following is a specification.

This invention relates to power apparatus for propelling ships or boats, and has for its object the provision of novel means actuated by any suitable motor and acting to draw in air through tunnel members or channels in the boat and also acting to cause a flow of water through a suitable conduit in the hull, these various drive or power elements co-operating to propel the boat through and along the water in a rapid manner and with the expenditure of comparatively little power.

An important and more specific object is the provision of a propelling mechanism of this character in which use is made of a plurality of longitudinally extending air passages or channels and a single water channel or conduit located longitudinally of and extending through the hull, it being possible to throw either or all of the different devices into operation at will depending upon circumstances.

An additional object is to provide a propelling apparatus of this character which will be comparatively simple and inexpensive in manufacture, easy to install and operate, positive in action, efficient and durable in service, and a general improvement in the art.

With the above and other objects and advantages in view, the invention consists in the details of construction and the arrangement and combination of parts to be herein-after more fully described and claimed, and illustrated in the accompanying drawings, in which:—

Figure 1 is a plan view of a boat or vessel equipped with the apparatus.

Figure 2 is an end elevation thereof.

Figure 3 is a vertical longitudinal section taken on the line 3—3 of Figure 1, and

Figure 4 is a vertical cross sectional view taken on the line 4—4 of Figure 3.

Referring more particularly to the drawings, the numeral 10 designates the hull of a ship or vessel which may be of wood, metal or any other desired construction and which

may be of any preferred size, these details being absolutely immaterial so far as the essence of the invention is concerned.

In carrying out the invention the hull is provided with a longitudinally extending conduit 11 which may be built thereinto in any desired manner and which may be of any desired cross sectional area, this conduit communicating with the body of water in which the vessel floats so that there will be unobstructed flow of the water from front to back or from stem to stern of the vessel.

Above the water line the vessel is further provided with a plurality of longitudinally extending passages 12 and 13 arranged in series and in superimposed relation, there being a plurality of the passages 12 located above a preferably corresponding number of passages 13. The cross sectional area of these passages is likewise an immaterial detail as variations may be resorted to if found advisable. At its rear end the conduit 11 is somewhat enlarged to define a casing 14 and the passages 12 and 13 are enlarged to define casings 15 and 16 respectively.

Suitably mounted within the interior of the hull is an engine 17 of any preferred type operating to drive the propeller shaft 18 which has the usual propeller 19 which is ordinarily located between the rear end of the hull and the rudder mechanism 20. Journaled transversely within the casing member 14 or enlargement at the rear end of the conduit 11 is a shaft 21 suitably geared to the propeller shaft 18 and carrying a propeller wheel 22 here represented as embodying a hub provided with radially extending curved arms or blades 23. Obviously, when this shaft 21 is rotated the rotation of the wheel 22 will operate to create suction upon the water within the conduit 11 so that the water will be drawn rearwardly along the conduit, resulting in forward movement of the vessel.

Journaled transversely through the casing members 15 and 16 at the rear ends of the passages 12 and 13 are shafts 24 and 25 respectively carrying propeller wheels 26 and 27 preferably of the same curved vane or blade type as the propeller wheel 22. The shafts 24 and 25 also carry bevel gears 28 and 29 meshing with bevel gears 30 and 31 respectively on the upper ends of vertical shafts 32 and 33 which have their lower ends carrying clutch elements 34 and 35 respec-

tively coating with similar clutch elements 36 and 37 carried by short shaft members 38 and 39 equipped with bevel gears 40 and 41 meshing with bevel gears 42 and 43 on 5 the propeller shaft 18. Obviously, any suitable lever mechanism or the like may be provided for throwing the clutch devices into or out of engagement depending upon whether it is desired to have the wheels 24 and 25 10 operate or not.

In the operation it is of course apparent that the rotation of the motor 17 will operate to drive the propeller shaft and the propeller will act to move the vessel forwardly 15 in the usual manner. At the same time, the rotation of the wheel or propeller member 22 will operate to draw the water rearwardly through the conduit 11 and thereby increase the forward movement of the vessel. If the 20 clutch members on the vertical shafts 32 and 33 are thrown into operative engagement it is quite clear that the wheels 24 and 25 driven thereby and located at the rear ends of the passages 12 and 13 will act to produce 25 air draft through these passages and this air draft will, by reaction, naturally operate to assist in the forward movement of the vessel. By properly manipulating whatever lever means is provided in connection with 30 the clutch devices any or all of these various drive devices may be thrown into or out of operation at will depending upon circumstances. It is really believed that the construction, operation and advantages will be 35 readily apparent to one skilled in the art without further explanation.

While I have shown and described the preferred embodiment of the invention, it should be understood that I reserve the right 40 to make such changes in the form, construction and arrangement of parts as will not depart from the spirit of the invention or the scope of the subjoined claims.

Having thus described the invention, I claim:

45

1. In a boat propelling mechanism, a hull provided below the water line with a longitudinally extending water conduit and above the water line with a plurality of longitudinally extending air passages, shafts journaled transversely of the air passages and the water conduit and carrying propeller wheels, and means for selectively driving said propeller wheels.

2. In a boat propelling mechanism, a hull 55 provided below the water line with a longitudinally extending conduit and above the water line with a plurality of banks of longitudinally extending air passages, shafts journaled transversely of the water conduit 60 and banks of air passages and carrying propeller wheels having curved vanes or blades, a motor, a shaft driven by the motor and carrying a propeller located at the stern of the hull, and means operatively connected 65 with said last named shaft for driving said propeller wheels.

3. In a boat propelling mechanism, a hull provided below the water line with a longitudinally extending conduit and above the 70 water line with a plurality of banks of longitudinally extending air passages, shafts journaled transversely of the water conduit and banks of air passages and carrying propeller wheels having curved vanes or blades, 75 a motor, a shaft driven by the motor and carrying a propeller located at the stern of the hull, and means operatively connected with said last named shaft for driving said propeller wheels, including vertically extending shafts operatively connected with the shaft of said propeller wheels, and clutch members interposed in said last named shafts.

In testimony whereof I affix my signature.

PAUL MEDIATE.
